Primary Examiner — Susan Moon Lee

CLAIM

The ornamental design for a device for wireless dog fence system, substantially as shown and described.

DESCRIPTION

FIG. 1 is a bottom, front and right side perspective view of a device for wireless dog fence system, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof; and,

FIG. 7 is a top plan view thereof.

The broken lines in the drawings illustrate the portions of the device for wireless dog fence system, which form no part of the claimed design.

1 Claim, 7 Drawing Sheets
